United States Patent Office

Des. 175,471
Patented Aug. 30, 1955

175,471

END SUPPORT FOR A TABLE AND BENCH COMBINATION

George N. Knox, Alliance, Ohio

Application October 21, 1953, Serial No. 27,264

Term of patent 14 years

(Cl. D33—14)

Fig. 2

Fig. 1

Fig. 1 is an elevational view of an end support for a table and bench combination, showing my new design;
Fig. 2 is a top plan view thereof.

I claim:

The ornamental design for an end support for a table and bench combination, substantially as shown.
